UNITED STATES PATENT OFFICE

EDWARD M. ROTHEN, OF NEW YORK, N. Y., ASSIGNOR TO RUSSELL & STOLL COMPANY, OF NEW YORK, N. Y., A CORPORATION OF NEW YORK

ILLUMINATING UNIT FOR SWIMMING POOLS

Application filed July 12, 1929. Serial No. 377,641.

This invention relates to improvements in illuminating units, the invention being particularly constructed for use in illuminating swimming pools or other bodies of water.

5 It is a primary object of the invention to provide an illuminating device of this character which can be used beneath the water level without injury to the light or any of its connections.

10 It is a further object to provide a device of the above character in which the lighting unit or fixture can be readily removed from its support beneath the water level to a point above the water level for re-lamping, repairing or replacing the fixture or any of its parts.

15 It is a still further object to provide a light of this character which will be cooled by the liquid from the pool.

20 The above and other objects will appear more fully from the following description when considered in connection with the drawings, in which:

25 Fig. 1 is a vertical sectional view, parts being in elevation, of one form which my invention may assume, showing the same applied to a pool illuminating apparatus.

Fig. 2 is an enlarged sectional view of the lamp or fixture and the wall housing.

30 Fig. 3 is a front elevational view, parts being in section, of the construction shown in Fig. 2.

Fig. 4 is an enlarged detail showing the method of attaching the lens and bezel to the 35 light casing.

The present invention is shown as applied to under-water illuminating devices for a swimming pool 6 formed of concrete or other substantial and permanent material 8. The 40 inner faces of the walls and bottom of the pool may be lined with tile or other material as indicated for example at 10.

The apparatus may be best applied to the pool during its construction, the same comprising a wall housing 12 formed with an open face 13 and a rearward closed portion 14 of slightly reduced proportions. The open exposed edge 13 is preferably arranged substantially flush with the inner face of the 50 wall 8 or its lining, if employed. The inter-

mediate portion of the side wall of the housing 12 may include a projecting flange or bead 15 for more permanently attaching the housing in the concrete or other material of which the wall 8 is formed. The wall housing includes an opening at 16 for receiving the lighting cable and its conduit or housing.

55 The housing 12 is further provided with lamp supporting devices indicated generally at 18. These devices, in the preferred form of the invention, include supporting members 20 secured in recesses at opposite sides of the housing 12. The members 20 are of general hook shape and are formed with depressions 21 to form sockets for receiving 60 the supporting lugs 22 mounted upon the opposite sides of the lighting fixture described in detail below.

65 The supporting members 20 are shown as facing upwardly so that the fixture may be 60 moved into place and rest upon the supports.

70 The lighting fixture indicated generally at 24 includes a body casing 26 of general conical shape and formed with a rearward portion 28 for receiving the lamp socket, electrical conductors, etc., and with a forward portion 30 for receiving the lens.

75 The inner face of the casing 26 has arranged thereon a series of radial vanes 32 formed integrally with the casing 26 and 80 projecting inwardly toward the light bulb referred to below. The vanes 32 extend around the light bulb, when the same has been assembled, and are provided particularly for the purpose of more readily absorbing 85 the heat from the light and dissipating the same through the cooling influence of the water surrounding the fixture 24. It will be understood that the number of vanes or ribs 32 and the exact proportions of the same 90 may be varied within wide limits in correspondence with the present invention.

95 Since the fixture 24 will be entirely surrounded by the liquid (water) from the pool it is necessary to completely seal every portion of the fixture to prevent the ingress of the water into the light fixture. To this end the lens 34, of any usual or preferred construction, has the edges thereof sealed by the rubber gaskets 35 and 36 in combination with 100

any suitable waterproof compound, these gaskets and the outer edge of the lens being received and compressed between the outer lens ring 38 and the bezel 40. The edges of the lens are formed with flattened surfaces 37 where the same are engaged by the rubber washers 35 and 36, this construction completely avoiding any tendency of leakage at this point. The ring 38 is, according to the present construction, drawn toward the bezel 40 and held in position by means of a series of machine bolts 42. The upper portion of the outer ring 38 is provided with a supporting handle 44 for facilitating the movement of the fixture to and from the wall housing 12.

It will thus be seen that the combined bezel, outer ring 38 and lens 34 may be handled as a unit and attached to or detached from the light casing 26 without disturbing the mounting for the lens 34. The combined lens and bezel is shown as attached to the casing 26 by means of a series of machine bolts 46 which may extend through the ring 38 and bezel 40 and into the outer lens supporting portion 30 of the casing. The portion 30 is formed with a recess for receiving the rubber or other gasket 48 to effectively seal the space between the bezel 40 and casing 26. A guide pin 47 is preferably employed to facilitate the assembling of the ring 38, bezel 40 and casing 26. This pin may, as shown in Fig. 2, be rigidly supported in the bezel 40, the projecting ends of the pin being received in suitable bore holes formed in the ring 38 and casing 26.

The interior of the light fixture is formed with a socket supporting plate 50 supporting the cable terminals and light socket 52, the latter receiving the bulb 54. A reflector 56 encircles the bulb 54 and is formed with the spaced parabolic reflecting portions 56a and 56b for scattering the rays of light within certain limits as will be readily understood.

Since the housing 12 and fixture 24 will be positioned beneath the water level of the body of water 6 these parts as well as the bezel 40 and ring 38 are constructed of non-corrosive material, for example bronze, so that the apparatus may be used even with salt water without destroying or harming the fixture or the wall housing for the same.

It will be noted that the support for the fixture 24 is such that the fixture may be tilted vertically to vary the inclination of the beam of light. The lamp is held in its adjusted position by devices preferably carried entirely by the fixture 24. To this end the rearward portion 28 of the light fixture is provided with a vertically adjustable rod or bar 58 received in a substantially vertical opening in one of the lugs 59 formed on the casing 26. The bar may be held in position by a set screw 60 or other suitable device.

By adjusting the rod 58 vertically prior to

the introduction of the fixture into its position within the housing 12, the angle of inclination of the lamp may be varied as desired.

Power is supplied to the bulb 54 by means of a water-proof cable 62. This cable passes inwardly into the interior of the casing 26 through an opening 63. The space within the opening 63 which surrounds the cable 62 is provided with compressible packing 64 and an adjustable nut for compressing the packing firmly around the cable 62 to prevent leakage through the opening 63.

The cable 62 passes upwardly through a cable conduit 66 and into a cable housing 68 positioned above the water level of the tank. These parts likewise are preferably formed of non-corroding material such for example as brass or bronze. The housing 68 is formed with sloping sides and bottom portion so that any liquid which may pass into the same will readily drain back into the conduit 66 and thence into the tank. The housing 68 is of sufficient proportions to accommodate several feet of excess cable which is normally stored therein when the apparatus is in use. The upper face of this housing is covered by a removable floor plate 69. It is preferred that the housing 68 be embedded in the concrete or other material of which the wall 8 is formed in order to avoid any possibility of disturbing the conduit 66 or its connections to the housings 12 or 68.

It will be observed that the terminals (not shown) for receiving the ends of the cable 62 are thus maintained out of contact with the water of the pool. The terminals at the light are sealed within the light casing and the power terminals at the housing 68 are waterproofed and are above the high water level.

In assembling and installing this apparatus and after the installation of the housings 12 and 68 in the wall or otherwise adjacent the body of water 6 the fixture is first completely assembled. In assembling this fixture it is provided with the socket 52 suitably connected to the cable 62, the bulb 54, reflector 56, bezel 40, lens 34, packing 64, etc. The mounting for the lens and the opening 63 around the cable 62 are thus completely sealed after which they may be tested for any leakage. The shaft 58 is adjusted to provide the desired angle of inclination for the light beam. The cable 62 may thereafter be passed upwardly through the pipe 66 and connected to the source of power at a point adjacent the cable housing 68. The position of the lighting fixture when completely assembled and connected to the power cable is indicated in dotted lines in Fig. 1. The fixture may then be carried downwardly beneath the water level to the

housing 12 while the cable 62 is drawn upwardly through the conduit 66. By a simple movement of the light fixture it is set in place upon the light supports 20. Thereafter the cable 62 is arranged within the housing 68 and the cover 69 placed in position over the same. Since the casing 26 is entirely surrounded by water the lamp is maintained at a normal operating temperature due in part to the heat absorbing capacity of the vanes 32.

5 If at any time the light becomes out of order as by reason of an injury to the bulb 54, the same may be readily unhooked from the supports 20 and removed to a position above the water of the pool, after which the lamp may be repaired or replaced. During the removal of the lamp from its housing 12 the cable 62 is drawn downwardly through the conduit 66 as will be understood from an 10 inspection of Fig. 1. When the fixture is again introduced into the housing 12 the cable is again withdrawn through the conduit 66 to a position of rest within the housing 68.

15 20 25 It will be understood that various modifications may be made in the apparatus without departing from the spirit of the invention.

30 What I claim as my invention is:

1. In an under-water illuminating device for a body of water surrounded by a stationary wall having a recess therein positioned beneath the normal water level, a stationary housing in said recess, a lighting fixture submerged in said water and detachably supported within said housing, means for supplying electric current to said fixture and means for detaching said fixture from said housing and removing the same to a position above said water level without disconnecting said current supplying means from said fixture.
2. In an under-water illuminating device, a support formed as a stationary fixture housing positioned beneath the normal level of said water, a water-tight electric lighting fixture, means on said fixture for removably supporting the same on said support with said fixture submerged in said water, extensible means for supplying electric current to said fixture when supported on said support and when removed therefrom and withdrawn to a position remote from said support.
3. In an under-water illuminating device for a body of water, a fixture support, a water-tight electric lighting fixture, means on said fixture for supporting the same on said support with said fixture submerged in said water, extensible means for supplying electric current to said fixture when supported on said support and when removed therefrom and withdrawn to a position remote from said support, said last-named means including a water-proof cable attached to
4. In an under-water illuminating device for a body of water and in combination with a retaining wall thereof, a fixture housing embedded in said wall, a fixture support secured adjacent said housing, a removable electric lighting fixture having means engageable with said fixture support, a cable housing embedded in said wall above the normal level of said body of water, a water-proof electric conducting cable positioned in said conduit and extending from said fixture to said cable housing and formed with an excess amount of cable normally positioned in said cable housing.
5. In an under-water illuminating device and in combination with a body of water to be illuminated, a lighting fixture support positioned adjacent said body of water beneath the water level thereof, a lighting fixture 90 removably supported on said fixture support, a cable housing positioned above the normal level of said water and a cable extending from said cable housing to a point adjacent said fixture support and operatively connected to said fixture.
6. In an under-water illuminating device for a body of water confined within fixed walls, a fixture housing formed of non-corrod़ing material and positioned beneath the normal level of said water, a water-tight electric lighting fixture normally positioned within said fixture housing, a conduit extending through said wall and terminating at a point above the normal level of said water 105 and an electrical conductor extending through said conduit to said housing for supplying electric current to said fixture.
7. In an under-water illuminating device for a body of water, a stationary fixture support positioned beneath the normal level of said water and exposed to said water, a lighting fixture engageable with said fixture support when submerged in said water, said support and fixture being formed with coacting separable supporting elements for readily attaching and detaching said fixture to and from said support.
8. In an under-water lighting fixture, an enclosed light casing formed with bulb-supporting means and with inwardly extending heat-absorbing projections directed toward said bulb and intimately associated with the material of said casing and means for conducting electric current to said bulb.
9. In an under-water lighting fixture, an enclosed light casing formed with bulb-supporting means and with inwardly projecting fins extending into the interior of said light casing and formed integrally with said

said fixture by a water-tight joint, a housing for excess cable and a liquid-tight cable-receiving conduit connecting said housing with said body of water, said cable housing being constructed to drain any liquid therefrom into said conduit.

70 75 80 85 90 95 100 105 110 115 120 125 130

1. In an under-water illuminating device and in combination with a body of water to be illuminated, a lighting fixture support positioned adjacent said body of water beneath the water level thereof, a lighting fixture 90 removably supported on said fixture support, a cable housing positioned above the normal level of said water and a cable extending from said cable housing to a point adjacent said fixture support and operatively connected to said fixture.

2. In an under-water illuminating device for a body of water confined within fixed walls, a fixture housing formed of non-corrod़ing material and positioned beneath the normal level of said water, a water-tight electric lighting fixture normally positioned within said fixture housing, a conduit extending through said wall and terminating at a point above the normal level of said water 105 and an electrical conductor extending through said conduit to said housing for supplying electric current to said fixture.

3. In an under-water illuminating device for a body of water, a stationary fixture support positioned beneath the normal level of said water and exposed to said water, a lighting fixture engageable with said fixture support when submerged in said water, said support and fixture being formed with coacting separable supporting elements for readily attaching and detaching said fixture to and from said support.

4. In an under-water lighting fixture, an enclosed light casing formed with bulb-supporting means and with inwardly extending heat-absorbing projections directed toward said bulb and intimately associated with the material of said casing and means for conducting electric current to said bulb.

5. In an under-water lighting fixture, an enclosed light casing formed with bulb-supporting means and with inwardly projecting fins extending into the interior of said light casing and formed integrally with said

casing and means for conducting electric current to said bulb.

10. In an under-water lighting fixture, an enclosed light casing formed with bulb-sup-

5 porting means and with a series of radial in- wardly projecting heat-absorbing elements formed integrally with said casing on the portion of said casing encircling said bulb.

11. In an under-water illuminating appa-

10 ratus, a fixture support, a lighting fixture pivotally and removably secured to said sup- port, adjustment means carried by said fix- ture, said adjustment means being engage- able with said support and adjustable with

15 respect to said fixture for adjusting the angle of inclination of said fixture when sup- ported on said support.

12. In an under-water illuminating appa-

20 ratus, a fixture support, a lighting fixture pivotally and removably secured to said sup-

port, means carried by said fixture for ad- justing the angle of inclination of said fix- ture, said means including a vertically ad- justable rod rigidly secured to said fixture

25 and engageable with said support and means for holding the same in any adjusted posi- tion.

13. An under-water illuminating device for a body of water surrounded by a station-

30 ary wall having a recess therein positioned beneath the normal water level, a lighting fixture detachably supported within said re- cess and means exterior to said wall for maintaining electrical connection to said fix- ture while permitting said fixture to be moved to a position above said normal water level.

14. An under-water illuminating device for a body of water surrounded by a station-

40 ary wall having a recess therein positioned beneath the normal water level, a lighting fixture detachably supported within said re- cess which forms a housing therefor and

45 means for maintaining electrical connection to said fixture while permitting said fixture to be moved outwardly from said recess and

then upwardly through said body of water to a position above said normal water level.

Signed at New York, in the county of New
50 York and State of New York, this 10th day of July, A. D. 1929.

EDWARD M. ROTHEN.
